BOOK-MARK HOLDER.

PHIL. TOMPPERT, Jr., OF LOUISVILLE, KENTUCKY.

Letters Patent No. 60,285, dated December 4, 1866.

SPECIFICATION.

TO ALL WHOM IT MAY CONCERN:

Be it known that I, PHIL. TOMPPERT, Jr., of Louisville, in the county of Jefferson, and State of Kentucky, have invented a new and improved Book-Mark Holder; and I do hereby declare that the following is a full, clear, and exact description thereof, which will enable others skilled in the art to make and use the same, reference being had to the accompanying drawings, forming part of this specification, in which—

Figure 1 is a front elevation of my invention.

Figure 2 is a back elevation of the same.

Figure 3 is a longitudinal section taken on the line $z z$, fig. 1.

Similar letters of reference indicate like parts.

My invention consists in a metallic clasp, consisting of a bent strip of metal having slots or perforations in its head portion, through which slots tapes or ribbons are passed, which, when the two legs of the device are clasped over a number of leaves of the book, can be thrown down between the leaves, to keep a place of reference in a book.

The simplest way of making the device is to stamp or cut out of a sheet of metal a piece having a larger portion, a , at its centre, and which tapers off into two legs, $b b$. The strip is then provided with slots through one side of the largest portion, and the two whole pieces bent over at about its middle. Tapes or ribbons are then to be drawn through the slots, and the device is complete. In using the device, the legs are caused to clasp a sufficient quantity of leaves, and, indeed, it may be placed on the top edges or corners of a book; the tape can be thrown down to keep a number of places of reference in a book. This is a simple and cheap little device, and answers well the purpose for which it is intended.

What I claim as new, and desire to secure by Letters Patent, is—

The ribbon-receiving slots a , in the book-mark herein described, whereby a place of reference may be marked, and opened by the ribbon, as and for the purpose specified.

The above specification of my invention signed by me this 28th day of February, 1866.

PHIL. TOMPPERT, Jr.
